UNITED STATES PATENT OFFICE.

EDWIN S. CALKINS, OF SOLVAY, NEW YORK, ASSIGNOR TO MILTON E. DAVIS, OF CANASTOTA, NEW YORK.

BRUSH AND MEANS FOR ATTACHING SAME TO HOSE OR HANDLES.

1,383,387.

Specification of Letters Patent.

Patented July 5, 1921.

Application filed May 22, 1920. Serial No. 383,554.

To all whom it may concern:

Be it known that I, EDWIN S. CALKINS, a citizen of the United States, and a resident of Solvay, in the county of Onondaga and State of New York, have invented a certain new and useful Brush and Means for Attaching Same to Hose or Handles, of which the following is a specification.

This invention has for its object a brush and means for attaching the brush to a handle, hose, pipe or nozzle, and the invention consists in the novel features, and in the combinations and constructions hereinafter set forth and claimed.

15 In describing this invention, reference is to be had to the accompanying drawings in which like characters designate corresponding parts in all the views.

Figure 1 is a plan view of a brush embodying my invention, the same being shown as mounted on a flexible hose pipe.

Figs. 2, 3 and 4 are sectional views on lines 2—2, 3—3, 4—4, Fig. 1, respectively.

Fig. 5 is a plan view of the detached clamp.

Fig. 6 is a plan view similar to Fig. 1 showing the brush attached to a nozzle.

This invention comprises a brush having two rearwardly extending arms or rods, 30 and a clamp having means for receiving and holding said arms, and means for securing to a part serving as a handle, as a stick, rod, hose, pipe or hose nozzle.

1 designates the brush which is here illustrated as comprising a twisted wire body 2 in the twists of which the bristles are held, the body being bent U shaped and terminating in rearwardly extending arms 3.

4 is the clamp which comprises a body 40 shaped to receive the part serving as a handle as the hose 5, Fig. 1, a nozzle 6, Fig. 6, and means for detachably securing it to the handle, hose, nozzles, etc.

The body of the clamp is composed of 45 two sections having arcuate jaw portions between their ends, the sections being hinged together at like ends and having means at their other ends for clamping the sections onto the handle, hose, etc.

50 As best seen in Figs. 3 and 5, one of the sections of the body is provided with an outwardly or radially extending flange 8

at one end, formed with a slot 9, and the other section is formed with a tongue 10 for entering the slot, the end projecting 55 through the slot being bent in the form of a hook or eye 11 around the end edge of said flange.

The sections of the body are formed at their other ends with spaced apart radial 60 flanges 12 through which a clamping screw 13 extends.

The means provided on the body of the clamp 4 for receiving the arms 3 of the brush comprises lugs provided on the section of the body on opposite sides thereof, 65 the lugs being spaced apart and arranged to be clenched onto the arms 3. Preferably, there are three lugs 15, 16, 17 on the outer side of the intermediate part of each section, the lugs 15, 16 being spaced apart in a direction lengthwise of the arm 3 engaged therewith, and the lug 17 being located opposite the space between the lugs 15, 16. These lugs constitute the opposite sides of 75 70 passages for the arms 3. After the arms are located between the lugs 17 and 15, 16, the lugs are clenched over onto the arms.

In Figs. 1 and 6, the arms 3 are shown as inclosed by a tube 18 which may serve 80 as a handle, and also, in Fig. 1, the hose 5 is shown as attached to one end of a valve casing 20 connected at its other end to a supply hose or pipe 21 for water. A spring pressed valve 22 is located in the casing to 85 control the flow of water to the brush, the valve being liftable from its seat 23 against the action of its spring 24 by a grip handle 25.

This device is particularly adapted for 90 use as a fountain brush attachment for hose, hose nozzles, etc. for washing wagons, automobiles, etc. On account of the sectional construction of the body and the hinge joint between the section and the arrangement of the lugs for holding the arms of the brush, the device is particularly economical in manufacture and readily attachable to a hose or nozzle without special construction in the hose or nozzle.

100 What I claim is:

The combination of a brush having a pair of rearwardly extending arms, and a clamp for attaching said arms to a part

serving as a handle, the clamp comprising a body mountable on said part, and having three lugs on each of two opposite sides thereof, for providing a passage for one of said arms, two of such lugs being spaced apart in a direction lengthwise of said arms, and the other being opposed to the space between the said two lugs, the lugs being

clenched onto the arms, substantially as and for the purpose described.

In testimony whereof I have hereunto signed my name, at Syracuse, in the county of Onondaga, and State of New York, this 17th day of April, 1920.

10

EDWIN S. CALKINS.
